UNITED STATES PATENT OFFICE.

HENRY BEZER, OF KINGSLAND, NEW JERSEY.

RAILWAY SIGNALING SYSTEM.

SPECIFICATION forming part of Letters Patent No. 716,179, dated December 16, 1902.

Application filed December 6, 1899. Renewed May 16, 1902. Serial No. 107,554. (No model.)

To all whom it may concern:

Be it known that I, HENRY BEZER, a subject of the Queen of Great Britain, and a resident of Kingsland, Bergen county, State of New Jersey, have invented certain new and useful Improvements in Railway Signaling Systems, of which the following is a specification, reference being had to the accompanying drawings, forming part hereof.

This invention relates to electric railway signaling systems, and has for its objects the protection of the circuits and apparatus from the interference of trolley-currents or other foreign currents and the sending of the signal to "danger" or maintaining the signal at "danger" in the event of breakage or failure of any rail, wire, or other part or parts under any conditions and also to provide that should any contacts become welded or adhere together or any coils or connections burn out, either before or after the signal has cleared for a train, the signal cannot indicate "safety" when it should indicate "danger."

In my improved signal there is no reliance upon automatic mechanism to change the signal from the indication of "safety" to that of "danger," and it is impossible for a signal to continue at "safety" behind a train.

The nature and objects of my invention will more fully appear from the following description of the accompanying drawings, illustrating embodiments of my invention.

Figure 1 is a plan view of the signal-box of a signal with the cover removed, partly in section. Fig. 2 is a transverse vertical section of the signal-box with the end removed. Fig. 3 is a longitudinal vertical section of the signal-box with the side removed. Fig. 4 is a front elevation of the complete signal, drawn to a reduced scale. Fig. 5 is a plan view of the signal-box of a modified form of signal, partly in section and with the cover removed. Fig. 6 is a transverse vertical section of the same with the end removed. Fig. 7 is a longitudinal vertical section of the same with the side removed. Fig. 8 is a side elevation of the signal-relay or rear relay and adjacent parts with the movable commutator-brush in rearward position. Fig. 9 is an enlarged detail of part of the movable commutator-brush and spring back contact. Fig. 10 is a diagrammatic representation of the circuits and

apparatus of a block signaling system. Fig. 11 represents a development of part of the commutator thereof. Fig. 12 is a diagrammatic representation of the circuits and apparatus of a block signaling system, showing a modified construction and arrangement thereof. Fig. 13 represents a development of part of the commutator thereof. Fig. 14 is a diagrammatic representation of the circuits and apparatus of a block signaling system, showing another modified construction and arrangement thereof; and Fig. 14^a is a similar view showing a further modification. Fig. 15 is a similar view of another modified construction and arrangement. Fig. 16 represents a development of part of the commutator thereof. Fig. 17 is a diagrammatic representation of the circuits and apparatus of a block signaling system with overlaps.

The signal shown in Figs. 1 to 4, inclusive, of the drawings is a motion - signal of improved construction giving the day safety indication by the continuous revolution of a medially-pivoted semaphore 1 (shown in Fig. 4) and the day danger indication with the semaphore 1 at rest in horizontal position and giving the night safety - signal by the flashing of the light of a lantern (not shown) resulting from the movement of the semaphore 1 in front of the lantern and the night danger indication by the steady and unobscured light of the lantern.

The semaphore and actuating mechanism are so constructed that the semaphore is free to swing to indicate "danger" and the weight of the semaphore is so disposed that the center of gravity of the semaphore is in a vertical line with the support when the signal is in the horizontal or danger position, and, as shown, the semaphore 1 is secured to the spindle 2 and mounted thereon at a point in the semaphore located medially as to the length of the semaphore, but considerably nearer one longitudinal edge of the semaphore than the other, (see Fig. 4,) so that the semaphore will gravitate to the horizontal position by its own weight. If desired, additional weights could be added, which would be located directly below the center of the spindle, with the semaphore in the position shown in Fig. 4. It will be observed that with this semaphore there is no reliance upon a stop to ar-

rest the semaphore when it reaches the horizontal position, and in consequence thereof there is no jar or concussion resulting from the movement of the semaphore to "danger" by 5 its own weight or counterweight. The semaphore will usually come to rest in the position shown in Fig. 4, with the center of gravity immediately below the pivotal axis of the semaphore, and in this position the semaphore 10 will be in stable equilibrium. It may possibly, however, be brought to rest in a diametrically opposite position, with the center of gravity immediately above the pivotal axis. This position would be one of unstable equilibrium, 15 from which the semaphore would gravitate to the position of stable equilibrium upon a slight disturbance of the poise or balance; but this position of unstable equilibrium would nevertheless be a horizontal position and would indicate "danger." Therefore the horizontal position is the only position of stable or unstable equilibrium which the semaphore can assume.

The semaphore-spindle has fixed upon it 20 the commutator K and also has fixed upon it one part of a clutch, whereby it may be connected with or disconnected from a train of gears actuated by the motor. This clutch is shown as an electromagnetic clutch comprising 25 a circular electromagnet and armature. The electromagnet D is secured to the semaphore-spindle and has an outer annular pole-piece and an inner pole-piece fitting about the spindle and a coil of insulated wire 30 in the annular space between the two pole-pieces. The armature D' and a gear-wheel 6 are secured together upon a non-magnetic sleeve D², loosely mounted upon the spindle 2. The gear-wheel 6 is the end gear of a train of 35 speed-reducing gears from the motor M, of which the pinion 3 is on the motor-shaft, and the gear 5, meshing with the pinion 3, and the pinion 4, meshing with the gear 6, are on an intermediate shaft 7. When the clutch-electromagnet D is energized, the armature D' is 40 held against it and the gear 6 and spindle 2 connected so as to rotate together; but when the clutch-electromagnet D is deenergized the gear and spindle are not connected, and 45 the semaphore 1 may swing to its normal position independently of the gears and motor.

The commutator K is shown as provided with two fixed brushes *h* and *i* and with one movable brush *f*. The two fixed brushes are 50 carried on an insulated block 11, having trunnions whereby it is held with freedom to oscillate in a carrier or bracket 12, secured to the side of the signal-box 8 and adjusted by a screw 13, which bears against the rear end of 55 the block above the axial line of the trunnions, so as to cause the brushes to bear against the commutator with the required pressure. This construction permits the commutator-brushes to be set up to compensate 60 for wear and also readily permits the cleaning of the commutator and generally facilitates the handling of the parts, as the loosen-

ing of the screw 13 and the raising of the commutator-brushes cuts the mechanism out of circuit.

70

The movable commutator-brush *f* is controlled by two opposed electromagnets G and H, each electromagnet being composed of a pair of coils, the coils of the front electromagnet G being joined by the bridge-piece 70 75 and the coils of the back electromagnet H being joined by the bridge-piece 71 and the two bridge-pieces being of magnetic material and being joined by non-magnetic supporting-bars 72 72. The armature-lever 16 is pivoted on a bearing-yoke 17, secured to but electrically insulated from the supporting-bars 72, and carries an armature 73, extending across between the pole-pieces of the electromagnets. This armature-lever has secured 80 to it the movable commutator-brush *f*, the upper end of which works under a contact-spring 23, which is a spring back contact, and the movable commutator-brush is clear of said spring when against the commutator 85 (see Figs. 7 and 9) and in contact with said spring when in backward position away from the commutator, with the armature-lever 16 in contact with the adjustable back-stop 74. (See Figs. 3 and 8.) The commutator-brush 90 is so constructed that upon first touching the contact-spring in moving backward away from the commutator it will not come in electrical contact therewith and, as shown, is provided with an insulated back 75, which 100 first comes in contact with the spring 23. This construction prevents chattering of the armature under conditions where the circuit through the front electromagnet G is momentarily closed, but not maintained, as will 105 be hereinafter described.

As shown, the contact-spring 23 is carried by a bracket 20, secured to upward extensions of the bridge-piece 71, but electrically insulated therefrom. The outer end of this contact-spring is curved, so as to surround a stop-pin 21, (see Fig. 9,) which limits its downward movement, and thereby prevents vibration of the spring after the movable commutator-brush *f* has moved clear of it, and this 110 stop-pin 21 is carried by lugs 22 22, which extend upward at each side of the end of the contact-spring. The stop-pin 21 also protects the contact-spring against distortion by accidental blows from above or below, and the 115 lugs 22 22 protect the contact-spring from side blows.

It is important to provide that the armature-lever may be so adjusted that the movable commutator-brush *f* will come in contact 120 with the commutator with the armature 73 just clear of contact with the poles of the front magnet G, so that with a light power from the track-circuit battery the movable brush will be held against the commutator, 125 and it is also important to provide for readjustment to compensate for wear of both the commutator and the movable brush; but it is 130 important that this adjustment should not dis-

turb the relative positions of the poles and armature. For this purpose I provide the bridge-piece 70 with an adjusting-screw 25, passing freely through a post 27 and having a nut 26, held against the outer face of the post by a spring 28 between the post and bridge-piece. The supporting-bars 72 72 are dovetailed to an insulating-block or stone base 29 and are united by the bearing-yoke 17, as well as by the bridge-pieces 70 71, and thus the entire relay will move on its base 29 without derangement of any parts thereof in either direction, according to the direction in which the nut is turned.

15 The back-stop screw 74 provides for the adjustment of the armature, so that under the conditions for giving the safety indications hereinafter described the armature 73 will be attracted away from the back magnet H and toward the front magnet G. The spring 76, encircling the rear portion of this stop-screw 74, acts to prevent shifting of the screw after it has been once adjusted.

For convenience in the assembling and taking apart of the mechanism the relay and adjusting device are carried on the stone base 29, which enters an opening in the bottom of the signal-box 8 and is secured to and carried by a plate 30, which overlaps the edges of the opening in the signal-box and is fastened to the bottom of the signal-box, as by the screws 80 shown, and the motor M is carried on a base 54, which rests upon the bottom of the signal-box between longitudinal guides 55 55, whereby it is held from lateral but not longitudinal movement and is held from longitudinal movement by a clamping-screw 56, entering a slot in the base 54, whereby the motor may be readily adjusted, so that its pinion 40 3 will mesh with the gear 5.

The bearings of the semaphore-shaft 2 and of the intermediate shaft 7 are shown as formed in brasses 9, mounted in the sides of the signal-box and all externally closed except the front bearing of the semaphore-shaft, and these brasses and the bearings of the motor-shaft are shown as fitted with automatic oilers 10.

Several terminals for outside wires are shown, each consisting of a metallic plate 57, into which enters from the outside a screw-post 58, passing upwardly through the stone base 29 and having a screw tapped therein for the outside wire and into which also enters from the inside one or more screws 59 for the inside wire or wires, this screw 59, or one of these screws 59, extending down into a clearance-hole in the stone base 29, thereby acting as a steady-pin to prevent the plate 57 from turning.

The relay above described having the opposed electromagnets G and H is the signal-actuating relay, as it brings the movable commutator-brush *f* into contact with the commutator K, and thereby causes the closing of the signal-actuating circuit. It is also

a rear relay, as it is located at the rear end of the block guarded by the signal.

I provide means for forcing the movable commutator-brush *f* into the position required for the danger indication, such means consisting of a cam L on the commutator K, such cam being of conductive material and in conductive contact with the main plate of the commutator. Once in every revolution this cam L forces the movable commutator-brush *f* away from the poles of the front electromagnet G and into contact with the contact-spring 23 and into such proximity to the poles of the back electromagnet H that under normal conditions, except where a normally open track-circuit is employed, and in such construction when the normally open track-circuit is closed, the armatures will be attracted toward these coils, and under no conditions, except under the effect of a preponderating current through the front electromagnet G, required for the safety indication, will the movable commutator-brush be returned to the commutator. A counterweight 77 is shown as provided on the armature-lever 16, (see particularly Fig. 8,) which tends to hold the armature always in rearward position; but this counterweight is not relied upon to bring the armature-lever to rearward position, the positive action of the cam L compelling this movement.

In the signal shown in Figs. 5 to 9, inclusive, there is no clutch between the motor and semaphore, and the signal is so constructed that the motor will always stop with the semaphore in the danger position. The semaphore and motor are always connected, and the gear 6 is secured to the semaphore shaft or spindle 2. I prefer also with this construction to mount the semaphore 1 upon its spindle medially both longitudinally and laterally, so that the weight of the semaphore is always equally balanced about the pivotal point. In this construction I have shown the form of rear relay hereinafter claimed, in which a local circuit assists the track-circuit in holding the movable commutator-brush *f* against the commutator. This relay is composed of two independent pairs of opposing coils X and Y, Z and W, the front coils being X and Z and the back coils Y and W. Each pair of opposing coils has cores magnetically connected, the pair of opposing coils X and Y having their cores connected by a soft-iron bridge or yoke 14, and the pair of opposing coils Z and W having their cores connected by the soft-iron bridge or yoke 15. The armature-lever 16 and its bearing-yoke 17 are of the same construction as heretofore described; but the armature is in two parts 18 19, magnetically insulated from each other, but rigidly secured together. The bracket 20, carrying the contact-spring 23, is secured to and insulated from the upper rear ends of the magnet-yokes 14 and 15, and the magnet-yokes 14 and 15 are joined at their front ends.

by a non-magnetic bridge-piece 24, to which is secured the adjusting-screw 25, above described.

The commutator K' (shown in Figs. 5 to 8, 5 inclusive) is also shown in development in Fig. 16, and the circuits coöperating therewith are illustrated in Fig. 15; but I will first describe the commutator K² (shown in development in Fig. 11) and the circuits coöperating therewith. (Illustrated in Fig. 10.) In this construction the several features of my invention hereinafter claimed are included, the relay having two independent pairs of opposed coils X and Y, Z and W, as before described, and the semaphore being mounted upon its spindle so as to gravitate to the danger position and being connected to the motor by a clutch, the clutch-magnet D being indicated and so lettered in Fig. 10. 10 This commutator K² is provided with three fixed brushes h, g, and i and with a movable brush f of the construction heretofore described and comprises a main plate 51, which is always in contact with the fixed brush h, 15 this main plate 51 having a lateral extension which is in contact with the brush g during a part of the revolution of the commutator and having a cam L thereon, as heretofore described, in electrical contact with the main 20 plate 51, and having an insulated or dead plate 52, which is in contact with the brush g when the lateral extension of the main plate 51 is not in contact therewith, and a separate insulated plate or conductive ring 25 53, which is always in contact with the fixed brush i and is connected to the clutch-magnet D. These commutator-plates 51, 52, and 53 are mounted upon a sleeve of insulating material and are separated from each other, 30 with intervening air-spaces and grooves in the insulating material coincident with the spaces between the plates, so that the rubbing action of the brushes cannot cause a conductive layer or deposit between the 35 plates.

Fig. 10 illustrates the complete circuits and apparatus of a single block A' and the circuits and apparatus at the front end of the adjacent block in rear, A. For each block a 40 front relay is provided. For the block A such relay comprises the two opposed electromagnets P and Q, which are connected in series with a track-battery B in a closed circuit from the battery B through wire 61, including resistance R, through coils P and wire 62, coils Q and wire 64, and back to battery, and having a normally open shunt-circuit, including the rails of block A and excluding the electromagnet Q, such shunt-circuit branching from the 45 circuit above described at the point 63 and running through the rails, when the rails are bridged by the wheels and axles of a train, and through wire 65 back to the battery. The relative normal magnetic attractions of the 50 coils of the two magnets P and Q are so adjusted relatively to the range of movement of the armature that under all normal conditions the

attractive force of the back electromagnet Q will preponderate in all positions of the armature to draw the armature toward this back 50 electromagnet; but when there is a train in the block A the closing thereby of the normally open shunt-circuit excluding the electromagnet Q will so weaken the attractive force of this magnet and strengthen the attractive 55 force of the electromagnet P that the armature p will be attracted toward the electromagnet P. This is preferably accomplished by adjusting the relative number of convolutions in the coils P and Q and the range of 60 movement of the armature so that the attractive force exerted upon the armature p by the magnet Q will be the greater under all conditions, except when there is a train in the block A. The armature p is therefore normally in 65 rearward position and is only moved from that position by the shunting action of a train in the block A. Block A' has a similar front relay, with opposed electromagnets P' Q' in a closed circuit from battery B' through wire 61', including resistance R', and through wires 62' and 64', and a normally open shunt-circuit branching from such closed circuit at the point 63'. The coils X and Y of the rear relay are connected to the rails at the rear end of 70 the block A' through wire 38, normally open points comprising an armature a and contact-stop b, wire 34, front coil X, wires 35 and 40, back coil Y, and wire 39. The first effect of the closing of the armature p on the contact 75 q resulting from the presence of a train in the block A is the closing of a circuit from the main battery B' through wire 31, (including the high-resistance electromagnet I, controlling the armature a,) through wire 35, contact 80 q, armature p, wire 36, contact r, armature s, and wire 37 back to battery. The current flowing through this circuit energizes the electromagnet I and closes the armature a on contact b, thereby closing the normally open break in 85 the conductors joining the coils X and Y with the rails and closing a circuit from the track-battery B' at the front end of block A' through the coils X and Y in series, as follows: from battery B' by wire 61', coil P', wire 62', the rail 90 of block A', which is shown above the other rail and which may therefore for convenience be termed the "upper" rail, the wire 38, armature a, contact b, wire 34, front coil X, wires 35, 40, back coil Y, and wire 39 to the 95 rail, which may be termed the "lower" rail of block A' and through wire 65' back to the battery. The current which tends to flow through this circuit would magnetize the two opposing poles of the coils X and Y, but would 100 not affect the armature 14, which is normally in close proximity, to the pole of back coil Y and at a considerable distance from the pole of front coil X; but this current is immediately overcome by a more powerful current 105 from the main battery B', which flows as follows: from the main battery B' through wire 31, wire 32, movable commutator-brush f, contact-spring 23, wires 33 38, armature a, con-

tact *b*, wire 34, front coil *X*, wire 35, contact *q*, armature *p*, wire 36, contact *r*, armature *s*, and wire 37 back to battery. The current of the battery *B'* also has a path through wires 31 and 32, movable commutator-brush *f*, contact-spring 23 and wire 33, and thence by wire 38 to the upper rail of block *A'* and through the wire 62', coils of magnet *P'*, wire 61', including resistance *R*², and through the track-battery *B'* to the lower rail of block *A'*, and through the coils of magnet *Q'* from the upper to the lower rail, and through the ground to some extent from the upper to the lower rail, and from the lower rail by wire 39, through the back coil *Y* and wire 40 to wire 35, and through wire 35, contact *g*, armature *p*, wire 36, contact *r*, armature *s*, and wire 37 back to battery. In this latter circuit there will be in one branch thereof the resistance due to the coils *P'* and resistance *R*² and to the opposition of the track-battery *B'*, the current of which will be met and overcome, and in another branch thereof the resistance of the coils *Q'*, and in another branch thereof the resistance of the ground, and in consequence a more powerful current will flow through the circuit above described from the main battery *B'*, including the front coil *X* and not including the rails of the track. Moreover, the direction of the flow of current through the front coil *X* in such circuit will be the same as that which flowed therethrough from the track-battery *B'*, whereas the direction of the flow of current through the back coil *Y* from the main battery *B'* will be the reverse of that which flowed therethrough from the track-battery *B'*, and the magnetism induced thereby in the core of the coil *Y* will be in opposition to the magnetism set up in the core of back coil *Y* by conduction from the core of the more powerfully energized front coil *X*. As a result of the powerful magnetization of the core of front coil *X* and of the demagnetization of the core of back coil *Y* the armature 14 will be more powerfully attracted toward the front coil *X*, and the movable brush *f* will be brought against the commutator and away from contact with the contact-spring 23. This movement of the movable commutator-brush breaks the energizing-circuit just described of the front coil *X* from the main battery *B'*; but as it brings the armature 14 close to the front coil *X* and as the current from the track-battery *B'* can now flow through both coils *X* and *Y* there will be sufficient magnetism at the pole of front coil *X* to hold the movable commutator-brush against the commutator, it being observed that the armature is now at its greatest distance from and practically out of the field of the back coil *Y*. I shall term the above-described circuit, which thus temporarily strongly energizes the front coil *X* from the main battery *B'*, the "front-coil" circuit. The movable commutator-brush *f* being now against the commutator closes the following actuating-circuit: From main bat-

tery *B'*, by wires 31 32, movable brush *f*, main commutator-plate 51, fixed brush *h*, wire 41, coil *Z*, wire 42, coil *W*, wire 43, high-resistance coils *S* and wire 44 and wire 37 back to battery. The current flowing through this actuating-circuit energizes the coils *S* and causes the armature *s* to be brought into contact with the stop *t*, thereby closing the motor-circuit and the clutch-circuit, such motor-circuit branching at the point 47 from the actuating-circuit and including wire 45, motor *M*, the coils of which are of low resistance, wire 46, stop *t*, and armature *s* and returning to the connections above described at the point 49, and such clutch-circuit branching from the actuating-circuit through the wire 66, connected to the main plate 51 of the commutator through the clutch-electromagnet *D*, wire 67, commutator-ring 53, brush *i*, and wire 68 and meeting the motor-circuit at the wire 46. The closing of the motor-circuit in multiple with the high-resistance coils *S* greatly diminishes the resistance of the circuit as a whole, and therefore greatly increases the magnetic attraction of the coil *Z*, and the attraction of this coil *Z* reinforces the attractive power of the coil *X*, thereby increasing the pressure of the movable brush *f*. While the closing of the motor-circuit also correspondingly increases the magnetic attraction of the coil *W*, the armature is now at its greatest distance therefrom, and therefore the attraction of the coil *Z* preponderates, and its preponderating power is increased by the closing of the motor-circuit.

The closing of the motor-circuit and clutch-circuit starts the rotation of the signal and the commutator *K*², and the rotation of the commutator brings the lateral projection of the main plate 51 thereof into contact with the fixed brush *g*, establishing supplementary actuating and motor and clutch circuits, which will be hereinafter described. As the commutator *K*² continues to revolve the cam *L* gradually forces the movable brush *f* into contact with the contact-spring 23, and at this time the brush *g* is in contact with the lateral projection of the main commutator-plate 51. So long during this movement as the movable brush is in contact with the cam *L*, and therefore electrically connected to the main plate 51 of the commutator, the circuit for the motor is as above described, and although the movable brush *f* may be in contact with the contact-spring 23 there is no circuit through that spring, because the armature *s* is against the contact *t* and away from the contact *r*. When the movable brush *f* has been forced by the cam *L*, so that the armature is in close proximity to the back coils and will be held or attracted by these back coils away from the commutator by the current from the track-battery *B'*, flowing through both coils *X* and *Y* in series, and the current from the main battery *B'*, flowing through the coils *Z* and *W* in series, because the armature has now been forced by the cam *L* into close proximity to

the poles of the back coils Y and W, and their attraction will therefore preponderate, the lateral projection of the main plate 51 of the commutator is still in contact with the brush 5 g, and the supplementary actuating-circuit, motor-circuit, and clutch-circuit, which were closed when the lateral projection of the main plate 51 passed under the brush g, are still maintained. The supplementary actuating-circuit is as follows: from the battery B', through wire 31, wire 48, fixed brush g, main commutator-plate 51, fixed brush h, wire 41, coil Z, wire 42, coil W, wire 43, coils S, wires 44 and 37, back to battery. The supplementary motor-circuit is a branch through the contact t of the actuating-circuit, as previously described, and the supplementary clutch-circuit is also a branch of said supplementary actuating-circuit, as previously described. When the lateral projection of the main commutator-plate 51 moves clear of the brush g, the supplementary actuating and motor and clutch circuits are opened, and at this point only can sparking take place, and this point is never wanted for the closing of the motor-circuit, as the actuating-circuit is closed by the contact of the movable commutator-brush f and the commutator and the motor-circuit closed by the movement of the armature S into contact with the point t, resulting from the energization of the electromagnet S by the actuating-circuit. Coils S being de-energized by the opening of the supplementary actuating-circuit, the armature s again comes against the contact r, and thereby closes the front-coil circuit above described, and then the previously-described circuit through movable brush f and spring-contact 23 is closed, providing the armature p is at that time against its contact q. There is a short interval between the breaking of the supplementary motor-circuit and the succeeding completion of the motor-circuit sufficient for the armature s to move from contact t to contact r and to close the front coil-circuit and for the movable commutator-brush f to be attracted into contact with the commutator and for the armature S to be again moved against the contact t; but during this brief interval the momentum of the semaphore causes it to continue its movement without noticeable diminution of speed. The armature p will remain against its contact q so long as the train is still in the block A, and the signal will continue to revolve under the action of these circuits until the train enters the block A' and for a sufficient time thereafter for the completion of the movement of the semaphore to a predetermined point of its revolution selected as the most desirable for the opening of the motor and clutch circuits. As shown, this point is such that the semaphore and commutator will be about one-fourth of a revolution in rear of the danger position when the motor and clutch circuits are opened.

When the train enters the block A', the cur-

rent of the track-battery B² is shunted from the coils X and Y. Should this shunting action take place when the fixed brush g is not in contact with the lateral projection of the main commutator-plate 51, the movable brush f will be kept in contact with the commutator by the current of the main battery B' through the coil Z, and the revolution of the signal 75 will be continued thereby until the brush f is forced back by the cam L; but before the movable brush f is thus forced back the fixed brush g has come in contact with the lateral projection of the main commutator-plate 51, 80 so that while the movable brush f is being forced backward into proximity to the back coils Y and W the completion of the revolution of the signal is assured by the supplementary actuating, motor, and clutch circuits, 85 above described, through the brush g. After the movable brush has been forced back so that its armature is near the poles of the back coils W and Y and the supplementary actuating, motor, and clutch circuits have been 90 opened by the passing of the lateral projection of the main commutator-plate 51 out of contact with the brush g, and thereby the magnet S has been de-energized and armature s dropped upon contact r the presence of the 95 train in block A' will prevent the placing of the movable commutator-brush f upon the commutator whether the points p and q have been opened by the passage of the train out of block A or are still kept closed by the shunting action of part of the train in block A. If the points p and q are still closed, the part of the train in block A' will close a circuit from the main battery B' through the back coil Y in multiple with the circuit from such battery 100 through the front coil X, which front-coil circuit would now be closed, as above described, and this current, through the back coil Y, is sufficiently powerful to hold the armature back. The circuit thus closed by the train 110 may be traced as follows: from battery B' through wires 31 32, movable brush f, contact 23, wires 33 38, upper rail, wheels and axles of train, lower rail, wire 39, back coil Y, wires 40 35, contact q, armature p, wire 36, contact 115 r, armature s, and wire 37 back to battery. The front-coil circuit from the main battery B' has heretofore been traced and is as follows: from battery B' by wires 31 32, movable brush f, spring-contact 23, wires 33 38, 120 armature a, contact b, wire 34, front coil X, wire 35, contact q, armature p, wire 36, contact r, armature s, and wire 37 back to battery. If the points p and q are open, then the magnet I is de-energized and all circuits of the 125 main battery B' are open, and the coils X and Y are de-energized, and the movable brush f will not be moved from its rear position. Should a following train now enter the block A and thereby close the armature p 130 upon its contact q, the presence of the train on block A' will prevent the actuation of the movable commutator-brush toward the commutator, not only by shunting the track-bat-

tery B², but also by closing a path of low resistance across the rails and through the rear coil Y, as above described. The coils X and Y will both be energized, and therefore the 5 movable commutator-brush will not be moved from its normal position in close proximity to the back coil Y, and the signal will not be moved from its normal danger position.

It is also to be noted that should there be 10 a break in the wires 39 or 40 and the circuits be otherwise intact with a consequent energization of the front coil X only there will be a magnetization of the core of the back coil Y by conduction through the yoke 14, and in 15 fact the inner end of core of back coil Y will become one of the poles of the front coil X, and should the armature 14 be nevertheless pulled toward the front coil X the forward movement of the commutator-brush will 20 carry it away from the spring-contact 23 and will thus break the energizing-circuit of the front coil X, and as the train on block A' shunts the current from the track-battery B² and there is a break in the connection of the 25 coils X and Y to the track there is no perceptible current to maintain the movable brush f in proximity to the front coil X and against the commutator, and it will be moved backward by its counterweight until its insulated back rests against the contact-spring 30 23, and the signal will continue at "danger."

It will also be observed that the breaking of a rail in the block A' would have the effect of cutting out the track-battery B², and this 35 would bring about the conditions above described upon the entrance of a train in block A—viz., the temporary closing of a circuit through the front coil X, which circuit would be broken by the forward movement of the 40 movable commutator-brush f, resulting from its own action, and would not be again closed by its return movement because of its insulated back. Therefore with a broken rail in 45 block A' a train in block A could not receive a safety-signal.

Should the armature p become welded to the contact q by a lightning stroke or otherwise caused to adhere to such contact, the signal would be changed to a normally clear 50 signal, but would go to "danger" whenever there was a train in block A'.

Should the armature s become welded to the contact r or caused to adhere to such contact, the motor-circuit could not be closed, and 55 therefore the signal could not be moved from the normal danger position. Should this armature s become welded or be caused to adhere to the contact t, the signal could only complete its revolution to the danger position. To cause it to start upon another revolution, it would be necessary to close the 60 brush-actuating circuit through the contact r and armature s. Should the armature a become welded or be caused to adhere to the 65 contact b, the track-battery circuit through the coils X and Y would remain always closed

instead of normally open; but the functions of that circuit would be undisturbed.

Should the movable commutator-brush f or any commutator-brush become welded to the 70 commutator, the signal could not revolve. Should the movable commutator-brush f become welded to the contact-spring 23 or adjustable back contact 74, the movable brush could not be brought into contact with the 75 commutator, and the motor-circuit could not be closed and the signal would remain at "danger."

One source of danger in railway signaling systems is the action upon the apparatus of 80 foreign currents, such as electric-light currents or trolley-currents. Such currents could not under any conditions cause a safety-signal in my system when the conditions of traffic required a danger-signal nor could 85 they interfere with the operation of the signals if the strength of the batteries were properly adjusted whenever such foreign currents were present.

A foreign current could only enter the system by exposed conductors, and the only exposed conductors are the rails. With trains in both blocks A and A' should the positive 90 of a foreign current enter the upper rail it cannot pass from the rail to any part of the 95 circuits of the rear relay without encountering the opposed current of the main battery B', which is flowing through the wire 38 to such rail, and the strength of this battery would usually be more than sufficient to oppose the entrance of the foreign current to the rear relay and under extraordinary conditions could readily be made strong enough for that purpose, and therefore the foreign current would be shunted through the wheels and 100 axles of the train. With no train in block A' and a train in block A there are two conditions 105 of the circuits, one where the front-coil circuit is closed and the other where the front-coil circuit is broken and the movable commuta- 110 tor-brush f is against the commutator. When the front-coil circuit is closed, the foreign current is met and opposed by the current of the main battery B' flowing through the wire 38 to the rail, and assists in the energization of 115 the front coil X by the battery B' as it adds to the resistance in the path of the battery B' by way of wire 38. When the front-coil circuit is broken, the easiest path for the foreign current is through the coils X and Y in series, 120 and it would therefore only assist in maintaining the armature forward and the brush f against the commutator.

Should the positive of a foreign current enter the lower rail and reach the wire 39 125 with trains in both blocks A and A', the foreign current can only enter the back coil Y of the rear relay, tending to assist the energization of that coil and the consequent maintenance of the danger indication. After passing through this coil it will encounter the current of the main battery B' flowing through 130

the wire 35 from the front coil X and can only flow with that current to and through the contact *q*, armature *p*, wire 36, contact *r*, armature *s*, wire 37, main battery *B'*, wires 31 and 32, movable commutator-brush *f*, contact-spring 23, and wires 33 and 38 to the upper rail. With a train in block A only the conditions will be as just described when the front-coil circuit is closed and the foreign 10 current will flow through the back coil only, tending to oppose the effort of the main battery *B'* to give a safety-signal and can be taken care of by providing sufficient battery power to overcome it. With the front-coil 15 circuit broken such a foreign current could only flow through both coils X and Y in series and would not therefore actuate the armature of the rear relay.

In the event of breakage of the wires connecting the battery *B'* the only path for the foreign currents would be through the coils X and Y in series.

From the above description it will be evident that the arrangement of the opposed 25 coils X and Y, connected in series with the rails or exposed conductors, makes it impossible to send a current through the front coil X without at the same time sending the same current through the back coil Y, and this will 30 be true also in the event of failure or breakage, and the connection of the main battery *B'* with the rails and the utilization of the current of this main battery to prevent the giving of a safety-signal while there is a train 35 in the block instead of relying wholly upon the shunting of the track-battery not only prevents the giving of a safety-signal by a foreign current in place of the track-battery current, but also interposes a strong counter- 40 acting force to any foreign current and makes it possible to prevent any interference by such external currents with the operation of the signal.

The foreign currents usually encountered 45 are not of great strength and can usually be taken care of in a system embodying my invention by ordinary battery-power, and, as aforesaid, the battery-power may be increased where necessary. Should, however, a foreign 50 current at any time exceed the strength provided against and overcome the battery-current, such foreign current could not do more than prevent the giving of a safety-signal and could not in any event cause a safety-signal 55 to be given when a danger-signal is required.

As heretofore stated the commutator and connections shown in Fig. 10 are arranged for a semaphore, such as is shown in Fig. 4, with its weight disposed so that it will gravitate to the danger position, and while the construction shown and above described provides for the continuation of the operation of the motor and clutch to a predetermined point, nevertheless should the motor or clutch fail at any point the semaphore would go to "danger" by the action of its own weight. With such a construction it is possible to use

a commutator and relay and circuits in which no means are provided for continuing the movement of the semaphore to a predetermined point, and such a construction of commutator and relay is shown in Figs. 1 to 4, inclusive, and the commutator is shown in development in Fig. 13, and an arrangement of circuits coöperating therewith is illustrated 75 in Fig. 12. In this construction the commutator *K* consists merely of a main plate 54 always in contact with the fixed brush *h* and having the cam *L* thereon coöperating with a movable commutator-brush *f*, as above described, and a conductive ring 53 always in contact with the fixed brush *i*. The rear relay, as above described, consists of opposed electromagnets *G* and *H*, and its operation is the same as that of the relay above described, 80 consisting of the coils *X Y Z W*, except that there is no assistance from the main or local battery to hold the movable brush *f* against the commutator. The means for normally breaking the track-circuit through the rear 85 or brush-actuating relay are also omitted and the wires 38 and 34 run directly to the relay without any break therein. A train in block A would close the points *p* and *q*, and thereby immediately close the front-coil circuit, and the movable brush *f* would directly 90 close the motor-circuit and clutch-circuit. The motor-circuit is as follows: from main battery *B'*, by wire 31, movable commutator-brush *f*, main commutator-plate 54, fixed 95 brush *h*, wire 55, motor *M*, and wire 37 back to battery. The clutch-circuit branches from the main commutator-plate 54 of the motor-circuit through wire 66, clutch-magnet *D*, wire 67, commutator-ring 53, brush *i*, 100 and wire 68 and joins the motor-circuit at the wire 37. These circuits remain closed until the train enters the block A' and shunts the current of the track-battery *B'*, and thereby so weakens the front magnet *G* that the 105 counterweight 77 pulls the armature and movable brush *f* back, and the movable brush *f* leaves the commutator. When the movable brush leaves the commutator, it opens the motor and clutch circuits and the semaphore is released and under the action of its 110 own weight and in its swinging movement in either direction will cause the cam *L* to force the movable commutator-brush into its rearward position. 115

In the modified construction shown in Fig. 14 the spring back contact 23 for the movable commutator-brush *f* is omitted, and the forcing-cam *L'* has only a sufficient elevation to insure the starting of the movement of the 120 armature away from the poles of the front magnet *G*. For the further rearward movement of the armature its counterweight is relied on. In other respects the brush-actuating or rear relay is as shown in Figs. 12 and 125 13 and heretofore described; but this construction includes the means for breaking the actuating-circuit shown in Fig. 10, such means including the electromagnet *S* and its 130

armature *s*, working against front contact *t* and back contact *r*. The fixed brush *h* is directly connected by the wire 43 to the electromagnet *S* and by the wires 43 and 45 to the electromotor *M*. This construction also includes the means, heretofore described and shown in Fig. 10, for breaking the track-battery circuit through the brush-actuating or rear relay, such means including the electromagnet *I*; but the arrangement is modified by not including the track-relay points *p* and *q* in the brush-actuating circuit and including these points only in the circuit of the electromagnet *I*. The actuating-circuit of magnet *I* may be traced as follows: from main battery *B'* by wire 31, magnet *I*, wire 56, contact *g*, armature *p*, and wire 37 back to battery. The front-coil circuit is as follows: from main battery *B'* by wire 31 57, armature *a*, contact *b*, wire 34, coils of front magnet *G*, wires 35 36, contact *r*, armature *s*, and wires 58 37 back to battery. The other circuits and the operations of the circuit are as heretofore described, except that the forward movement of the movable brush *f* does not break the front-coil circuit, but such circuit is broken by the closing of the actuating-circuit through the electromagnet *S* and the consequent opening of the points *r* and *s*.

In Fig. 14^A I have shown a construction of rear relay or brush-actuating relay from which the back electromagnet is omitted. Here the wire 35 is connected directly to the wire 39, leading to the lower rail. In this construction the rear relay has but one pair of coils *G* connected to the rails or exposed conductors; but the current of the main battery is utilized to prevent the giving of a safety-signal under the action of foreign currents. The presence of a train in the block causes a shunt-circuit to be closed for the main battery *B'*, which shunt-circuit is as follows: from main battery *B'* through wire 31, movable brush *f*, spring-contact 23, wires 33 38, upper rail, wheels and axles of train, lower rail, wire 39, wire 35, including resistance *R*³, armature *p*, contact *q*, and wires 36 37 back to battery. The current output of the main battery *B'* is limited by the dead resistance *R*³, and the relay-armature is at such a distance from the poles of the magnet *G* that the current from the track-battery cannot attract the relay-armature and that this shunt-circuit will prevent a sufficient energization of the electromagnet *G* for the attraction of the armature, and consequently after the movable brush *f* has been moved back by the cam *L* it cannot be again attracted into contact with the commutator. It will also be observed that in the construction shown in Fig. 14^A the circuit for the electric clutch *D* passes from the fixed brush *i* by wire 68, armature *p*, contact *q*, and wires 36 and 37 back to battery, and thus the closing of the clutch-circuit is dependent upon the closing of the contacts *p* and *q*, and the clutch-circuit cannot be closed without also closing the circuit which enables

the main battery to oppose the action of foreign currents. The resistance to the track-battery current through the rear relay may be decreased, however, without omitting the back coil *Y* or the back electromagnet *H* by winding the back coil *Y* or the coils of the back electromagnet *H* so that their resistance will be considerably less than that of the front coil or coils, but so that when the circuit of the main battery *B'* flows through front and back coils in multiple, as hereinbefore described, the magnetic force of front and back coils would be substantially equal. By this winding the resistance of the back coil or coils may be reduced to a minimum, and although when a current passed through them in series the front coil or coils would be stronger than the back coil or coils the previously-described normal proximity of the armature to the pole or poles of the back coil or coils would cause the attractive force of this coil or coils to normally preponderate and hold the armature back.

Fig. 15 shows a construction including a rear relay having opposed pairs of coils *X* and *Y* and *Z* and *W*, as in Fig. 10, but with no break in the wires from the coils *X* and *Y* to the rails, so that the circuit for the track-battery *B'* through these coils is permanently closed. The signal mechanism for this construction is precisely as shown in Figs. 5 to 9, inclusive, and above described; the clutch being omitted and the semaphore-spindle and motor-shaft permanently connected. An alteration is here made in the position of the track-relay, the coils being shown as arranged vertically instead of horizontally. The operation of the circuits is as heretofore described. The means for always completing the revolution of the semaphore to a predetermined point are as heretofore described and are so constructed as to open the motor-circuit at such a point that the motor and semaphore will come to rest from the exhaustion of their own momentum with the semaphore in the horizontal or danger position.

In the several constructions and arrangements illustrated in Figs. 10, 12, 14, 14^A, and 15 and above described I have made no provision for overlaps or arrangements of home and distant signals, and I prefer not to use such constructions, as they necessarily introduce some reliance upon automatic mechanism in changing from the indication of "safety" to that of "danger," the danger provision of the overlap involving reliance upon automatic mechanism and the change from distant safety to distant danger involving reliance upon automatic mechanism. I have indicated in these views the means for obtaining the protection to a train at the rear end of a block afforded by such constructions. I provide in rear of each indicating-signal, of which two, *J* and *J*², are shown, a dummy signal, of which one, *C*², for the indicating-signal *J*², is shown, such dummy signal being located at such a distance from the indicating-signal that under

clear conditions of weather the indicating-signal will always be visible from the train at the dummy signal and that under all conditions the train can be brought to a stop between the two signals and at no greater distance from the indicating-signal than is necessary to bring trains under such control that they can be stopped in rear of the indicating-signal. The function of the dummy signal is to notify the train-engineer that he has reached the point at which he must observe and obey the indicating-signal, and the rule of running should be that upon reaching the dummy signal the train-engineer should look at the indicating-signal, and if it is at "danger" he should bring his train to a stop before reaching the indicating-signal, and if it is at "safety" he may proceed at full speed. If, therefore, a train has broken down or stopped just in front of a signal, as the signal J^2 , so that the signal J' of the block it has just passed out of, A' , will give the safety indication to a following train, this following train may proceed at full speed past this indicating-signal and until it reaches the dummy signal C^2 located near the front end of the block A' . Upon reaching this dummy signal the train-engineer looks at the indicating-signal J^2 at the front end of the block, finds it at "danger," and brings his train to a stop before reaching the indicating-signal J^2 , and therefore at a safe distance in rear of the train first mentioned, which must necessarily have passed beyond this signal. It will be seen that by the employment of this dummy signal there is a substantial saving of running time, as the following train proceeded at full speed until it reached the dummy signal. The only conditions under which such dummy signal would not effect a saving of time would be when the weather was so foggy that the indicating-signal could not be observed from a train at the dummy signal. Under such conditions of weather the train-engineer upon reaching the dummy signal and not being able to see the indicating-signal would have to apply his brakes and slow down his train ready to stop at the indicating-signal until he could see the indicating-signal, but could immediately put on full speed upon seeing a safety indication at the indicating-signal.

The particular construction of the dummy signal is unimportant. I have indicated a post, with the letter "C" for "Caution," upon which a green light may be placed at night. The construction just described secures all the benefits of an overlap or an arrangement of home and distant signals. I have illustrated, however, an embodiment of other features of my invention in a signaling system, including an overlap, such construction being shown in Fig. 17. In this modified construction the rear-relay and the signal circuits are as shown in Fig. 15 and above described; but the circuits of the front relays are altered, and an additional relay is provided at the front end of each overlap, an overlap relay, consisting of opposed electromagnets E and

F , being shown at the front end of overlap a' in block A' . One side of the track (shown as the upper one) is divided into insulated sections, each extending from the front of one overlap to the front of the adjacent overlap, and the other side of the track (shown as the lower one) is divided into insulated sections, each extending from end to end of a block. Normally the current of track-battery B flows through wire 61, coils P , wire 62, coils Q , and wire 64 back to battery. When, however, a train enters block A , it closes a normally open shunt-circuit, as follows: from battery B , by wire 61, coils P , wire 65, contact u , armature v , wires 66 and 68, upper rail, and the wheels and axles of the train, to the lower rail, and from thence by wire 64 back to battery. The operations will then be as heretofore described for the giving of a safety-signal, it being noted that the current from the track-battery B^2 bridges the break in the conductivity of the upper rail by way of wire 67, coils E , and wire 68.

When the train enters the overlap a' , its wheels and axles close a shunt-circuit including the coils E of the overlap relay and excluding the coils F thereof and also including the coils P' and excluding the coils Q' of the front relay of block A^2 , such circuit being as follows: from battery B^2 by wire 61', coils P' , wire 65', through a contact and armature (not shown) corresponding to the contact u and armature v , and wires (not shown) corresponding with the wires 66 and 68, and then through the upper rail, wire 67, coils E , wire 68, upper rail of overlap a' , wheels and axles of train, lower rail, and wire 64' back to battery. The current flowing through this circuit causes the armature v to be attracted away from the contact u and against the contact w , thereby breaking the shunt-circuit, excluding coils Q , above described, and thereby closing a circuit from a main battery for block A corresponding to the battery B' , through the back coil Y of the rear relay of block A in multiple with the circuit from such battery through the front coil X of such relay, replacing the action of a train in block A in closing such a circuit. This circuit would be the same as heretofore described relative to the other constructions, except between the upper and lower rail, and its path from the upper to the lower rail would be as follows: from upper rail of block A and overlap a' , by wires 68 66, armature v , contact w , and wires 70 64, to lower rail of block A , and, in addition, the circuit of the track-battery B of block A will be opened at the points u and v , and therefore this track-battery cannot energize the rear relay of block A .

I have indicated in the various drawings illustrative of circuits embodying my invention resistances of the various coils such as 130 would be well adapted for the carrying out of my invention. In the construction illustrated in Fig. 10 a resistance of one-tenth of an ohm is indicated for the front coils, as P' ,

of the front relay, and of twenty-four ohms for the back coils, as Q', of the front relay, and the front coil X and the back coil Y of the rear relay are each indicated as having a resistance of three ohms. The other coils Z W of the rear relay are indicated as each having a resistance of one thirty-second of an ohm. A resistance of fifty ohms is indicated for the coils S and also for the coils I. The resistances R and R² are indicated as each of one ohm and are provided to interpose a resistance in the shunt-circuit, as is desirable with types of battery having very low internal resistance. With other types of battery, however, these resistances may be omitted. These resistances may be varied within wide limits—as, for example, although the low resistance of the front coils, as P', of the front relay diminishes the dead resistance in the operating track-circuit of the rear relay, and the high resistance of the back coils, as Q', of the front relay diminishes the output of battery-power in the permanently-closed branch circuit including these coils, the effectiveness of the front relay alone would be improved by more nearly equalizing or making equal the resistances of its front and back coils.

In the construction shown in Fig. 12 the track-circuits are normally closed, and here the resistance of the back coils, as Q', of the front relay is indicated as of twelve ohms, the resistance of the front coils, as P', remaining the same as in the normally open track-circuit construction illustrated in Fig. 10. The pair of front coils G of the rear relay are here indicated as having a total resistance of three ohms and the pair of back coils H thereof as having a total resistance of three ohms.

In the construction shown in Fig. 14 the track-circuits are normally open, as in Fig. 10, and the resistances here indicated are the same as in Fig. 10, the pair of front coils G having a total resistance equal to that of the single front coil X of Fig. 10 and the pair of back coils H having a total resistance equal to that of the single back coil Y of Fig. 10.

In the construction shown in Fig. 14^A the track-circuits are normally closed and the coils of the front relay are indicated as having the same resistances as in Fig. 12. The single pair of coils G of the rear relay is indicated as having a resistance of eight ohms. The resistance R³, indicated as of two ohms in the wire 35, is employed to prevent short-circuiting of the main battery B'.

In the construction shown in Fig. 15 the track-circuits are normally closed and the resistances of the coils of the front relay are as indicated in Fig. 12 and of the coils of the rear relay as indicated in Fig. 10. The resistance R', indicated as of one-fourth of an ohm in the wire 48 and therefore in the supplementary motor-circuit, is for the purpose of diminishing the speed of the motor when energized by this circuit.

In the construction shown in Fig. 17 the

track-circuit is normally closed and the resistances are the same as indicated in Fig. 15. The front coils E and the rear coils F of the overlap relay are indicated as of the same resistances as the corresponding coils of the front relays.

It is evident that various other modifications may be made in the circuits and apparatus above described within the purview of my invention and that parts of my invention may be used with other apparatus or instruments and in other circuits than those above described.

What I claim, and desire to secure by Letters Patent, is—

1. In a signaling system, the combination with the rails of a track, of a non-polar relay having opposed coils and an armature between said coils, said relay having its opposed coils connected in series with such rails, and means for sending an electric current differentially through such coils, substantially as set forth.

2. In a signaling system, the combination with the rails of a track, of a non-polar relay having opposed coils and an armature between said coils, said relay having its opposed coils connected in series with such rails in proximity to the rear end of a block or section and a source of electric energy connected to the rails in proximity to the front end of the block or section, and means for closing a circuit through one of said opposed coils to cause a movement of the armature of said relay, substantially as set forth.

3. In a signaling system, the combination, with exposed conductors of a block or section constructed so as to be bridged by a train, of a source of electric energy, and of a relay having opposed coils and having an armature between said coils, one side of one coil and one side of the source of electric energy being connected to an exposed conductor, and the other side of this coil and one side of the other coil being connected to the other side of the source of electric energy, and the other side of the last-named coil being connected to another exposed conductor, and additional means for sending an electric current through such exposed conductors, substantially as set forth.

4. In a signaling system, the combination, with an exposed conductor of a block or section, of a source of electric energy and a relay and means for opposing the current of such source of electric energy, between the relay and exposed conductor, to adverse foreign currents flowing through such exposed conductor, substantially as set forth.

5. In a signaling system, the combination, with exposed conductors of a block or section, of a source of electric energy, a non-polar relay having opposed coils connected to such exposed conductors in series and having an armature between said coils, and means for employing the current of such source of electric energy to oppose the efforts of foreign

currents to actuate such relay, and additional means for sending an electric current through such exposed conductors, substantially as set forth.

- 5 6. In a signaling system, the combination with exposed conductors of a block or section and of adjacent blocks or sections in front and in rear thereof, of one or more sources of electric energy connected to the exposed conductors of each of such blocks or sections in proximity to the front end and in proximity to the rear end of each block or section, the connections at the adjacent ends of different blocks being independent one of another and the 10 connections at opposite ends of the same conductor being of like polarity, and electromagnetic signal-operating means connected to such exposed conductors, substantially as set forth.
- 15 7. In a signaling system, the combination, with exposed conductors of a block or section constructed so as to be bridged by a train, of a relay and a source of electric energy, one side of the relay and one side of the source of electric energy being connected to an exposed conductor in proximity to the rear end of the block or section, and the other side of the relay and the other side of the source of electric energy being connected to another exposed conductor 20 in proximity to the rear end of the block or section, a circuit make-and-break device controlled by such relay and included in the connection of such source of electric energy to one of the exposed conductors, and means for sending an electric current through such exposed conductors from the front end of the block or section, substantially as set forth.
- 25 8. In a signaling system, the combination, with exposed conductors of a block or section 30 constructed so as to be bridged by a train, of a source of electric energy, and of a relay having opposed coils and having an armature between said coils, one side of one coil and one side of the source of electric energy being 35 connected to an exposed conductor in proximity to the rear end of the block or section, and the other side of this coil and one side of the other coil being connected to the other side of the source of electric energy, and the 40 other side of the last-named coil being connected to another exposed conductor in proximity to the rear end of the block or section, and means for connecting a source of electric energy to the exposed conductors in proximity to the front end of the block or section, substantially as set forth.
- 45 9. In a signaling system, the combination, with exposed conductors of a block or section, of a source of electric energy and a relay and 50 means for employing the current of such source of electric energy in proximity to the rear end of the block or section in opposition to the efforts of foreign currents to actuate said relay and means for connecting a source 55 of electric energy to the exposed conductors in proximity to the front end of the block or section, substantially as set forth.

10. In a signaling system, the combination, with exposed conductors of a block or section, of a non-polar relay having opposed coils and an armature between said coils, said relay having its opposed coils connected in series with such exposed conductors in proximity to the rear end of the block or section, and means for conveying an electric current to such exposed conductors in proximity to the front end of the block or section, and additional means for connecting a source of electric energy to such relay whereby the coils thereof are differentially energized, substantially as set forth. 70 75 80

11. In a signaling system, in combination, a signal and means for actuating the same, a relay and means for causing a forward movement of the armature of said relay and for holding said armature forward by circuits subject to the control of a train in advance of the signal, a contact device with two separated contact-points and a contact part capable of contacting with only one of said points 90 at a time, one of said contact-points being included in the circuit for causing the forward movement of the relay-armature, a circuit for operating the signal, including the other of said contact-points, and means for closing a 95 circuit by the forward movement of the relay-armature to actuate such contact part and thereby to break the circuit for causing the forward movement of the relay-armature and to close the circuit for operating the signal, substantially as set forth. 100

12. In a signaling system, in combination, a signal and means for actuating the same, a relay and means for closing a circuit to cause a forward movement of the armature of said 105 relay and opening said circuit by such forward movement of the relay-armature and supplying electric current to said relay to hold said armature forward from a circuit subject to the control of a train in advance of the signal, a contact device including a contact part and a contact-point, a circuit for operating the signal including such contact-point, and means for closing a circuit by the forward movement of the relay-armature and 110 causing said circuit to actuate such contact device and thereby to close the circuit for operating the signal, substantially as set forth. 115

13. In a signaling system, in combination, a signal and means for actuating the same, a 120 relay and means for closing a circuit to cause a forward movement of the armature of said relay and opening said circuit by such forward movement of the armature and supplying electric current to said relay to hold said 125 armature forward from a circuit subject to the control of a train in advance of the signal, and means for closing a circuit by the forward movement of the armature for causing the operation of the signal-actuating 130 means, substantially as set forth.

14. In a signal system, in combination, a signal and means for actuating the same, a relay and means for causing a forward move-

ment of the armature of said relay and for holding said armature forward by circuits subject to the control of a train in advance of the signal, a contact device including a coil 5 of high resistance, a contact part and a contact-point, a circuit for operating the signal of low resistance including such contact-point, and means for closing a circuit through such coil of high resistance by the forward movement 10 of the relay-armature and causing said circuit to actuate such contact device and thereby to close the circuit for operating the signal in multiple with such coil of high resistance and thereby to increase the magnetic force holding the relay-armature forward, 15 substantially as set forth.

15. In a signaling system, in combination, a signal and means for actuating the same, a relay and means for closing a circuit to cause 20 a forward movement of the armature of said relay and opening said circuit by such forward movement of the relay-armature and supplying electric current to said relay to hold said armature forward from a circuit 25 subject to the control of a train in advance of the signal, a contact device including a coil of high resistance, a contact part and a contact-point, a circuit for operating the signal of low resistance including such contact-point, and means for closing a circuit through such coil of high resistance by the forward movement 30 of the relay-armature and causing said circuit to actuate said contact device and thereby to close the circuit for operating the signal in multiple with such coil of high resistance and thereby to increase the magnetic force holding the relay-armature forward, substantially as set forth.

16. In a signaling system, in combination, 40 a signal and means for actuating the same, a relay and means for energizing said relay to cause a forward movement of the armature of said relay by a circuit subject to the control of a train in advance of the signal and opening said circuit by such forward movement 45 of the armature and supplying electric current to said relay to hold said armature forward from another circuit subject to the control of a train in advance of the signal, and means for closing a circuit by the forward movement of the armature for causing the operation of the signal-actuating means, substantially as set forth.

17. In a signaling system, in combination, 55 a signal and means for actuating the same, a relay and means for energizing said relay to cause a forward movement of the armature of said relay by a circuit subject to the control of a train in advance of the signal and opening said circuit by such forward movement 60 of the armature and supplying electric current to said relay to hold said armature forward from another circuit subject to the control of a train in advance of the signal, a contact device including a contact part and a contact-point, a circuit for operating the signal including such contact-point, and means

for closing a circuit by the forward movement of the relay-armature and causing said circuit to actuate said contact device and thereby to close the circuit for operating the signal, substantially as set forth. 70

18. In a signaling system, in combination, a signal and means for actuating the same, a relay and means for energizing said relay to 75 cause a forward movement of the armature of said relay by a circuit subject to the control of a train in advance of the signal and opening said circuit by such forward movement of the armature and supplying electric current 80 to said relay to hold said armature forward from another circuit subject to the control of a train in advance of the signal, a contact device including a coil of high resistance, a contact part and a contact-point, a circuit for 85 operating the signal of low resistance including such contact-point, and means for closing a circuit through such coil of high resistance by the forward movement of the relay-armature and causing said circuit to actuate 90 such contact device and thereby to close the circuit for operating the signal in multiple with such coil of high resistance and thereby to increase the magnetic force holding the armature forward, substantially as set forth. 95

19. In a signaling system, in combination, a signal and means for actuating the same, a commutator moving with the signal, a relay, a movable commutator-brush actuated by the armature of said relay, means for energizing 100 said relay to cause a forward movement of the armature thereof and for holding said armature forward with said movable brush against the commutator by circuits subject to the control of a train in advance of the signal, a contact device and a circuit for operating the signal, and means for closing a circuit by the movable brush through the commutator and causing said circuit to actuate such contact device and thereby to close the 110 circuit for operating the signal, substantially as set forth.

20. In a signaling system, in combination, a signal and means for actuating the same, a commutator moving with the signal, a relay, 115 a movable commutator-brush actuated by the armature of said relay, means for closing a circuit for causing a forward movement of the armature of said relay and supplying electric current to said relay to hold said armature forward with said movable brush against the commutator from a circuit subject to the control of a train in advance of the signal, a contact device including a contact part and a contact-point, a circuit for 120 operating the signal including such contact-point, and means for closing a circuit by the movable brush through the commutator and causing said circuit to actuate such contact device and thereby to close the circuit for 130 operating the signal, substantially as set forth.

21. In a signaling system, in combination, a signal and means for actuating the same, a

commutator moving with the signal, a relay, a movable commutator-brush actuated by the armature of said relay, means for closing a circuit for causing a forward movement of the armature of said relay and opening said circuit by such forward movement of the armature and supplying electric current to said relay to hold said armature forward with said movable brush against the commutator 10 from a circuit subject to the control of a train in advance of the signal, and means for closing a circuit by the movable commutator-brush through the commutator for causing the operation of the signal-actuating means, 15 substantially as set forth.

22. In a signaling system, in combination, a signal and means for actuating the same, a commutator moving with the signal, a relay, a movable commutator-brush actuated by the 20 armature of said relay, means for causing a forward movement of the armature of said relay and for holding said armature forward with the movable brush against the commutator by circuits subject to the control of a 25 train in advance of the signal, a contact device, and means for closing a circuit of high resistance by the movable commutator-brush through the commutator and causing said circuit to actuate such contact device and there- 30 by to close a circuit of low resistance for causing the operation of the signal-actuating means and thereby to increase the magnetic force holding the movable commutator-brush against the commutator, substantially as set 35 forth.

23. In a signaling system, in combination, a signal and means for actuating the same, a commutator moving with the signal, a relay, a movable commutator-brush actuated by the 40 armature of said relay, means for closing a circuit to cause a forward movement of the armature of said relay and opening said circuit by such forward movement of the relay- armature and supplying electric current to 45 said relay to hold said armature forward with the movable brush against the commutator from a circuit subject to the control of a train in advance of the signal, a contact device, and means for closing a circuit of high resistance 50 by the movable commutator-brush through the commutator and causing said circuit to actuate such contact device and thereby to close a circuit of low resistance for causing the operation of the signal-actuating means 55 and thereby to increase the magnetic force holding the movable commutator-brush against the commutator, substantially as set forth.

24. In a signaling system, in combination, 60 a signal, and means for actuating the same, a commutator moving with the signal, a relay, a movable commutator-brush actuated by the armature of said relay, means for energizing said relay to cause a forward movement of the 65 armature and movable commutator-brush by a circuit subject to the control of a train in advance of the signal and opening said cir-

cuit by such forward movement and supplying electric current to said relay to hold said armature forward with the movable commutator-brush against the commutator from another circuit subject to the control of a train in advance of the signal, and means for closing a circuit by the movable commutator-brush through the commutator for causing the 75 operation of the signal-actuating means, substantially as set forth.

25. In a signaling system, in combination, a signal and means for actuating the same, a commutator moving with the signal, a relay, 80 a movable commutator-brush actuated by the armature of said relay, means for energizing said relay to cause a forward movement of the armature of said relay by a circuit subject to the control of a train in advance of the signal 85 and opening said circuit by such forward movement and supplying electric current to said relay to hold said armature forward with the movable commutator-brush against the commutator from another circuit subject to 90 the control of a train in advance of the signal, a contact device and means for closing a circuit of high resistance by the movable commutator-brush through the commutator and causing said circuit to actuate such contact 95 device and thereby to close a circuit of low resistance for causing the operation of the signal-actuating means and thereby to increase the magnetic force holding the movable commutator-brush against the commu- 100 tator, substantially as set forth.

26. In a signaling system, in combination, a signal and means for actuating the same, a commutator moving with the signal, a relay, a movable commutator-brush actuated by the 105 armature of said relay, means for energizing said relay to cause a forward movement of the armature and movable commutator-brush by a circuit subject to the control of a train in advance of the signal and opening said circuit 110 by such forward movement and supplying electric current to said relay to hold said armature forward with said movable commutator-brush against the commutator from another circuit subject to the control of a train 115 in advance of the signal, a contact device, and means for closing a circuit by the movable commutator-brush through the commutator and causing said circuit to actuate such contact device and thereby to close a circuit for 120 causing the operation of the signal-actuating means, substantially as set forth.

27. In a signaling system, the combination, with the track of a block or section, of a source of electric energy connected to the 125 track in proximity to the front end of the block or section and a non-polar relay having opposed coils and an armature between said coils, the coils of said relay being connected to the track in proximity to the rear end of 130 the block or section and so as to form a track-circuit from the source of electric energy through the relay, a signal controlled by the relay, and means for holding normally open

and for closing the track-circuit, such means being subject to control in rear of the signal, substantially as set forth.

28. In a signaling system, the combination, with the track of a block or section, of a source of electric energy connected to the track in proximity to the front end of the block or section, and a front relay having opposed coils and an armature between said coils and connected to the source of electric energy and to the track in proximity to the front end of the block or section, and a rear relay having opposed coils and an armature between said coils, the coils of the rear relay being connected in series to the track in proximity to the rear end of the block or section, a signal controlled by the armature of said rear relay, and means for holding normally open and for closing the track-circuit through such rear relay, such means being subject to control in rear of said signal, substantially as set forth.

29. The combination, with a signal and a commutator moving therewith of a movable commutator-brush and a relay controlling the same and means for energizing said relay, said relay including means for moving said brush toward or from the commutator and magnetically holding said commutator-brush in either extreme position, and circuit-completing means coöperating with such commutator and movable brush, substantially as set forth.

30. The combination with a signal and a commutator moving therewith, of a movable commutator-brush and an armature controlling the same, opposed coils having poles between which said armature is movable, means for differentially energizing said coils and circuit-completing means coöperating with such commutator and movable brush, substantially as set forth.

31. The combination with a signal and a commutator compelled to move therewith, of a movable commutator-brush and a relay controlling the same, and means for energizing said relay, said relay including means for moving said commutator-brush toward or from the commutator and magnetically holding said brush in either extreme position, and means on said commutator for forcing said commutator-brush away from said commutator, and circuit-completing means coöperating with such commutator and movable brush, substantially as set forth.

32. The combination, with a signal and a commutator compelled to move therewith, of a movable commutator-brush and an armature controlling the same, opposed coils having poles between which said armature is movable, and means on said commutator for forcing said commutator-brush away from said commutator and forcing said armature away from its forward position, means for differentially energizing said coils and circuit-completing means coöperating with such commu-

tator and movable brush, substantially as set forth.

33. The combination, with a signal and a commutator compelled to move therewith, of a movable commutator-brush and an armature controlling the same, opposed coils having poles between which said armature is movable, and a cam of conductive material on said commutator constructed to come in contact with such commutator-brush and force the same away from the commutator and the armature away from its forward position, means for differentially energizing said coils and circuit-completing means coöperating with such commutator and movable brush, substantially as set forth.

34. A signal with its weight disposed so that the signal is in equilibrium and the center of gravity thereof is at the greatest distance below the support when the signal is in the danger position, in combination with means for causing said signal to give a safety indication, substantially as set forth.

35. A pivoted semaphore-blade with its pivot located substantially medially of its length but so that the semaphore-blade is in equilibrium and the center of gravity thereof is at the greatest distance below the support when the signal is in the danger position and means for causing said signal to give a safety indication, substantially as set forth.

36. A signal free to swing to indicate danger and with its weight disposed so that the signal is in equilibrium and the center of gravity thereof is at the greatest distance below the support when the signal is in the danger position, in combination with means for causing said signal to give a safety indication, substantially as set forth.

37. A medially-pivoted semaphore-blade free to swing to indicate danger and with its weight disposed so that the semaphore-blade is in equilibrium and the center of gravity thereof is at the greatest distance below the pivot when the signal is in the danger position, in combination with means for causing said semaphore-blade to give a safety indication, substantially as set forth.

38. The combination, with a signal having its weight disposed so that the signal is in equilibrium and the center of gravity thereof is at the greatest distance below the support when the signal is in the danger position, a motor, means connecting the motor and signal, such means including an electric clutch, and means for energizing the electric clutch and actuating the motor, substantially as set forth.

39. The combination, with a signal having its weight disposed so that the signal is in equilibrium and the center of gravity thereof is at the greatest distance below the support when the signal is in the danger position, a motor, means connecting the motor and signal, such means including an electric clutch, a commutator moving with the signal, a mov-

able commutator-brush and means for actuating the same and closing a circuit through the movable commutator-brush and commutator to energize the electric clutch and actuate the motor, substantially as set forth.

40. The combination, with a signal having its weight disposed so that the signal is in equilibrium and the center of gravity thereof is at the greatest distance below the support 10 when the signal is in the danger position, a motor, means connecting the motor and signal, such means including an electric clutch, and means for energizing the electric clutch and actuating the motor and always continuing 15 the movement of the signal under the control of the motor to a predetermined point, substantially as set forth.

41. The combination, with a signal, of a motor, means connecting the motor and signal, such means including an electric clutch, 20 a commutator moving with the signal, and having a main plate connected to one side of such clutch and a separate plate connected to the other side thereof, a movable commutator-brush arranged to come in contact with the main plate and a fixed commutator-brush 25 in contact with the separate plate, and means for closing a circuit through the movable commutator-brush and main plate of commutator to actuate the motor and completing a circuit through said movable brush, main plate of commutator, electric clutch and separate plate of commutator and fixed brush thereof to energize said clutch, substantially 30 as set forth.

42. In a signaling system, in combination, a signal and means for actuating the same, a relay and means for closing a circuit through the coils of such relay to actuate the armature thereof and opening said circuit by such movement of the armature and supplying electric current to said relay to hold the armature in the position to which it has been moved from a circuit subject to the control 40 of a train in advance of the signal, and means for closing a circuit by the armature for causing the operation of the signal-actuating means, and means compelled to move with the signal in giving the safety indication and 45 by such movement forcing the armature in the direction required for the danger indication, substantially as set forth.

43. In a signaling system, in combination, a signal and means for actuating the same, a 55 relay having opposed coils and an armature between said coils, means for closing a front-coil circuit to cause a forward movement of said armature and for holding said armature forward by a circuit through front and back coils subject to the control of a train in advance of the signal, and means for closing a circuit by the forward movement of said armature for causing the operation of the signal-actuating means, substantially as set 60 forth.

44. In a signaling system, in combination, a signal and means for actuating the same, a

relay having opposed coils and an armature between said coils, means for closing a front-coil circuit to cause a forward movement of 70 said armature and opening the front-coil circuit by the forward movement of such armature, and for holding said armature forward by a circuit through front and back coils subject to the control of a train in advance 75 of the signal, and means for closing a circuit by the forward movement of said armature for causing the operation of the signal-actuating means, substantially as set forth.

45. In a signaling system, in combination, a signal and means for actuating the same, a relay having opposed coils and an armature between said coils, means for closing a front-coil circuit to cause a forward movement of 85 said armature and for holding said armature forward by a circuit through front and back coils subject to the control of a train in advance of the signal, a contact device including a contact part and a contact-point, a circuit for operating the signal including such contact-point, and means for closing a circuit by the forward movement of said armature and compelling said circuit to actuate said contact device and thereby to close the circuit 90 for operating the signal, substantially as set forth.

46. In a signaling system, in combination, a signal and means for actuating the same, a relay having opposed coils and an armature 10 between said coils, means for closing a front-coil circuit to cause a forward movement of said armature and opening the front-coil circuit by the forward movement of such armature, and for holding said armature forward 10 by a circuit through front and back coils subject to the control of a train in advance of the signal, a contact device including a contact part and a contact-point, a circuit for operating the signal including such contact-point, 11 and means for closing a circuit by the forward movement of said armature and causing said circuit to actuate such contact device and thereby to close the circuit for operating the signal, substantially as set forth. 115

47. In a signaling system, in combination, a signal and means for actuating the same, a relay having opposed coils and an armature between said coils, means subject to the control of a train in advance of the signal for 120 closing a front-coil circuit to cause a forward movement of said armature and for holding said armature forward by a circuit through front and back coils, and means for closing a circuit by the forward movement of said armature for causing the operation of the signal-actuating means, substantially as set 125 forth.

48. In a signaling system, in combination, a signal and means for actuating the same, a 130 relay having opposed coils and an armature between said coils, means subject to the control of a train in advance of the signal for closing a front-coil circuit to cause a forward

movement of said armature and opening the front-coil circuit by the forward movement of such armature, and for holding said armature forward by a circuit through front and back coils, and means for closing a circuit by the forward movement of said armature for causing the operation of the signal-actuating means, substantially as set forth.

49. In a signaling system, in combination, a signal and means for actuating the same, a relay having opposed coils and an armature between said coils, means subject to the control of a train in advance of the signal, for closing front-coil circuit to cause a forward movement of said armature and for holding said armature forward by a circuit through front and back coils, a contact device including a contact part and a contact-point, a circuit for operating the signal including such contact-point, and means for closing a circuit by the forward movement of said armature and causing said circuit to actuate such contact device and thereby to close the circuit for operating the signal, substantially as set forth.

50. In a signaling system, in combination, a signal and means for actuating the same, a relay having opposed coils and an armature between said coils, means subject to the control of a train in advance of the signal for closing a front-coil circuit to cause a forward movement of said armature and opening the front-coil circuit by the forward movement of such armature and for holding said armature forward by a circuit through front and back coils, a contact device including a contact part and a contact-point, a circuit for operating the signal including such contact-point, and means for closing a circuit by the forward movement of said armature and causing said circuit to actuate such contact device and thereby to close the circuit for operating the signal, substantially as set forth.

51. In a signaling system, in combination, a signal and means for actuating the same, a relay having pairs of opposed coils and an armature between said coils, means for closing a circuit through the front coil of one of said pairs of coils to cause a forward movement of said armature and for holding said armature forward by a circuit through the front and back coils of such pair of coils subject to the control of a train in advance of the signal, and means for closing a circuit by the forward movement of said armature, through another pair of opposed coils in said relay, and for causing the operation of the signal-actuating means, substantially as set forth.

52. In a signaling system, in combination, a signal and means for actuating the same, a relay having pairs of opposed coils and an armature between said coils, means for closing a circuit through the front coil of one of said pairs of coils to cause a forward movement of said armature and opening the front-coil circuit by the forward movement of such armature and for holding said armature forward

by a circuit through the front and back coils of such pair of coils subject to the control of a train in advance of the signal, and means for closing a circuit by the forward movement of said armature, through another pair of opposed coils in said relay, and for causing the operation of the signal-actuating means, substantially as set forth.

53. In a signaling system, in combination, a signal and means for actuating the same, a relay having pairs of opposed coils and an armature between said coils, means subject to the control of a train in advance of the signal for closing a circuit through the front coil of one of said pairs of coils to cause a forward movement of said armature and for holding said armature forward by a circuit through the front and back coils of such pairs of coils, and means for closing a circuit by the forward movement of said armature through another pair of opposed coils in said relay and for causing the operation of the signal-actuating means, substantially as set forth.

54. In a signaling system, in combination, a signal and means for actuating the same, a relay having pairs of opposed coils and an armature between said coils, means subject to the control of a train in advance of the signal for closing a circuit through the front coil of one of said pairs of coils to cause a forward movement of said armature and opening the front-coil circuit by the forward movement of such armature and for holding such armature forward by a circuit through the front and back coils of such pair of coils, and means for closing a circuit by the forward movement of said armature through another pair of opposed coils in said relay and for causing the operation of the signal-actuating means, substantially as set forth.

55. In a signaling system, in combination, a signal and means for actuating the same, a relay having pairs of opposed coils and an armature between said coils, means for closing a circuit through the front coil of one of said pairs of coils to cause a forward movement of said armature and for holding said armature forward by a circuit through the front and back coils of such pair of coils subject to the control of a train in advance of the signal, an electromagnet with coils of high resistance and the armature thereof, a signal-operating means of low resistance, and means for closing a circuit, by the forward movement of the relay-armature, in series through front and back coils of a second pair of opposed coils in said relay and the coils of said electromagnet and for closing, by the resulting actuation of the armature of said electromagnet, a branch of said last-mentioned circuit through such signal-operating means of low resistance in multiple with the coils of said electromagnet, substantially as set forth.

56. In a signaling system, in combination, a signal and means for actuating the same, a relay having pairs of opposed coils, and an armature between said coils, means for closing

- a circuit through the front coil of one of said pairs of coils to cause a forward movement of said armature and opening the front-coil circuit by the forward movement of such armature and for holding said armature forward by a circuit through the front and back coils of such pair of coils subject to the control of a train in advance of the signal, an electromagnet with coils of high resistance and the armature thereof, signal-operating means of low resistance, and means for closing a circuit, by the forward movement of the relay-armature, in series through front and back coils of a second pair of opposed coils in said relay and the coils of said electromagnet, and for closing, by the resulting actuation of the armature of said electromagnet, a branch of said last-mentioned circuit through such signal-operating means of low resistance in multiple with the coils of said electromagnet, substantially as set forth.
57. In a signaling system, in combination, a signal and means for actuating the same, a relay having pairs of opposed coils and an armature between said coils, means subject to the control of a train in advance of the signal for closing a circuit through the front coil of one of said pairs of coils to cause a forward movement of said armature and for holding said armature forward by a circuit through the front and back coils of such pair of coils, an electromagnet with coils of high resistance and the armature thereof, signal-operating means of low resistance, and means for closing a circuit, by the forward movement of the relay-armature, in series through front and back coils of a second pair of opposed coils in said relay and the coils of said electromagnet and for closing, by the resulting actuation of the armature of said electromagnet, a branch of said last-mentioned circuit through such signal-operating means of low resistance in multiple with the coils of said electromagnet, substantially as set forth.
58. In a signaling system, in combination, a signal and means for actuating the same, a relay having pairs of opposed coils and an armature between said coils, means subject to the control of a train in advance of a signal for closing a circuit through the front coil of one of said pairs of coils to cause a forward movement of said armature, and opening the front-coil circuit by the forward movement of such armature and for holding such armature forward by a circuit through the front and back coils of such pair of coils, an electromagnet with coils of high resistance and the armature thereof, signal-operating means of low resistance, and means for closing a circuit, by the forward movement of the relay-armature, in series through front and back coils of a second pair of opposed coils in said relay and the coils of said electromagnet and for closing, by the resulting actuation of the armature of said electromagnet, a branch of said last-mentioned circuit through such signal-operating means of low resistance in multiple with the coils of said electromagnet, substantially as set forth.
59. In a signaling system, in combination, a signal and means for actuating the same, a relay having pairs of opposed coils and an armature between said coils, means subject to the control of a train in advance of a signal for closing a circuit through the front coil of one of said pairs of coils to cause a forward movement of said armature, and opening the front-coil circuit by the forward movement of such armature and for holding such armature forward by a circuit through the front and back coils of such pair of coils, an electromagnet with coils of high resistance and the armature thereof, signal-operating means of low resistance, and means for closing a circuit, by the forward movement of the relay-armature, in series through front and back coils of a second pair of opposed coils in said relay and the coils of said electromagnet and for closing, by the resulting actuation of the armature of said electromagnet, a branch of said last-mentioned circuit through such signal-operating means of low resistance in multiple with the coils of said electromagnet, substantially as set forth.

resistance in multiple with the coils of said electromagnet, substantially as set forth.

59. In a signaling system, the combination, 70 with a signal, of exposed conductors of a block or section constructed so as to be bridged by a train, a source of electric energy connected to such exposed conductors in proximity to the front end of the block or section, a relay having pairs of opposed coils and an armature between said coils, the cores of each pair of opposed coils being magnetically connected, one pair of opposed coils being connected in series to such exposed conductors in proximity to the rear end of the block or section, and an actuating-circuit of the signal including contacts controlled by the armature of said relay and connected so that the coils of said pair of opposed coils may be differentially energized, and including another pair of such opposed coils, substantially as set forth.

60. In a signaling system, in combination, 90 a signal and means for actuating the same, a commutator moving with the signal, a relay having opposed coils and an armature between said coils, the cores of each pair of opposed coils being magnetically connected, a movable commutator-brush actuated by 95 the armature of said relay, means for closing a front-coil circuit to cause a forward movement of said armature and for holding said armature forward with the movable brush against the commutator by a circuit through 100 front and back coils subject to the control of a train in advance of the signal, and means for closing a circuit by the movable brush through the commutator for causing the operation of the signal-actuating means, substantially as set forth.

61. In a signaling system, the combination with a signal, of exposed conductors of a block or section constructed so as to be bridged by a train, a source of electric energy connected 110 to such exposed conductors in proximity to the front end of such block or section, a relay having pairs of opposed coils, and an armature between said coils, the cores of each pair of opposed coils being magnetically connected, one pair of opposed coils being connected 115 in series to such exposed conductors in proximity to the rear end of the block or section, an electromagnet with coils of high resistance, signal-operating means of low resistance, and 120 means for closing a circuit, by the armature of said relay, in series through a second pair of opposed coils of said relay and the coils of said high-resistance electromagnet and for closing, by the resulting actuation of the armature of said electromagnet, a branch of 125 said last-mentioned circuit through such signal-operating means of low resistance in multiple with the coils of said electromagnet, substantially as set forth.

62. In a signaling system, in combination, 130 a signal and means for actuating the same, a commutator moving with the signal, a relay having opposed coils, and an armature be-

tween said coils, a movable commutator-brush actuated by the armature of said relay, means subject to the control of a train in advance of the signal for closing a front-coil circuit to 5 cause a forward movement of said armature and opening said front-coil circuit by such movement and for holding said armature forward with the movable brush against the commutator by a circuit through front and back 10 coils, and means for closing a circuit by the movable brush through the commutator for causing the operation of the signal-actuating means, substantially as set forth.

63. In a signaling system, in combination, 15 a signal and means for actuating the same, a commutator moving with the signal, a relay having pairs of opposed coils, and an armature between said coils, the cores of each pair of opposed coils being magnetically connected, 20 a movable commutator-brush actuated by the armature of said relay, said commutator being provided with means for forcing said movable brush away from said commutator and forcing said relay-armature rearwardly, 25 means for closing a circuit through the front coil of one of said pairs of coils to cause a forward movement of said armature and for holding said armature forward with the movable brush against the commutator by a circuit 30 through front and back coils of such pair of coils subject to the control of a train in advance of the signal, and means for closing a circuit by the movable commutator-brush through the commutator and through front 35 and back coils of another pair of opposed coils in said relay and for causing the operation of the signal-actuating means, substantially as set forth.

64. In a signaling system, in combination, 40 a signal and means for actuating the same, a commutator moving with the signal, a relay having pairs of opposed coils and an armature between said coils, the cores of each pair of opposed coils being magnetically connected, 45 a movable commutator-brush actuated by the armature of said relay, said commutator being provided with means for forcing said movable brush away from the commutator and forcing said relay-armature 50 away from its forward position, means for closing a circuit through the front coil of one of said pairs of coils to cause a forward movement of said armature, and for holding said armature forward with the movable brush against the commutator by a circuit through 55 the front and back coils of such pair of coils subject to the control of a train in advance of the signal, an electromagnet with coils of high resistance and the armature thereof, signal-operating means of low resistance, 60 and means for closing a circuit by the movable commutator-brush through the commutator and in series through front and back coils of a second pair of opposed coils in said 65 relay and the coils of said electromagnet and for closing by the resulting actuation of the armature of said electromagnet, a branch of

said last-mentioned circuit through such signal-operating means of low resistance in multiple with the coils of said electromagnet, substantially as set forth. 70

65. In a signaling system, the combination with a signal, of the rails of a block or section, a source of electric energy connected to the rails in proximity to the front end of the block or section, a relay having pairs of opposed coils and armature between said coils the cores of each pair of opposed coils being magnetically connected, a commutator moving with said signal, a movable commutator-brush controlled by the armature of said relay, said commutator being provided with means for forcing said movable brush away from said commutator, and forcing said relay-armature away from its forward position, 80 one pair of opposed coils of said relay being connected in series to the rails in proximity to the rear end of the block or section, an electromagnet with coils of high resistance, signal-operating means of low resistance, and 85 means for closing a circuit by the movable commutator-brush through the commutator and in series through front and back coils of a second pair of opposed coils in said relay and the coils of said electromagnet and for 90 closing, by the resulting actuation of the armature of said electromagnet, a branch of said last-mentioned circuit through such signal-operating means of low resistance in multiple with the coils of said electromagnet, substantially as set forth. 95

66. In a signal, the combination with a commutator and a movable commutator-brush, of a relay the armature of which carries said movable commutator-brush, said relay carrying the bearings of the armature, and means for adjusting as a whole relatively to the commutator said relay and the movable commutator-brush carried by the armature thereof, substantially as set forth. 105

67. In a signal, the combination with a commutator and a movable commutator-brush, said commutator being provided with means for forcing said movable brush away from the commutator, of a relay the armature of which carries said movable commutator-brush, said relay having opposed coils and said relay carrying the bearings of the armature, and means for adjusting as a whole relative to the commutator said relay and the movable commutator-brush carried by the armature thereof, substantially as set forth. 115

68. In a signaling system, in combination, a signal and means for actuating the same, a contact device with two separated contact-points and a contact part capable of contacting with only one of said points at a time, one of said contact-points being included in a circuit for causing the actuation of such contact part, a circuit for operating the signal including the other of such contact-points, and means for closing the circuit through such contact part and one of said points and thereby causing the movement of said contact de- 125 130

vice so as to bring the contact part in contact with the other point and thereby closing the circuit for operating the signal, and opening said last-mentioned circuit at intervals in the 5 operation of the signal subject to the closing of the first-mentioned circuit to continue the actuation of the signal, substantially as set forth.

69. In a signaling system, in combination, 10 a signal and means for actuating the same, a contact device with two separated contact-points and a contact part capable of contacting with only one of said points at a time, a relay and means for causing a forward movement 15 of the armature of said relay by a circuit closed through such contact part and one of said contact-points and for holding said armature forward by another circuit, a circuit for operating the signal including the other of 20 said contact-points and means for closing a circuit by the forward movement of said relay-armature and causing said circuit to actuate said contact device so as to bring the contact part in contact with the other point and there- 25 by closing the circuit for operating the signal, and opening said last-mentioned circuit at intervals in the operation of the signal subject to the closing of the first-mentioned circuit to continue the actuation of the signal, sub- 30 stantially as set forth.

70. In a signaling system, in combination, a signal and means for actuating the same, a commutator moving with the signal, a relay, a contact device with two separated contact- 35 points and a contact part capable of contacting with only one of said points at a time, a movable commutator-brush actuated by the armature of said relay, means for energizing said relay to cause a forward movement of 40 the armature thereof by a circuit closed through such contact part and one of said contact-points and for holding said armature forward with said movable brush against the commutator by a circuit subject to the con- 45 trol of a train in advance of the signal, a circuit for operating the signal including the other of such contact-points, and means for closing a circuit by the movable commutator-brush through the commutator and causing 50 said circuit to actuate said contact device so as to bring the other point in contact with such contact part and thereby to close the circuit for operating the signal and opening said circuit at the commutator at intervals in 55 the movement of the signal subject to the closing of the first-mentioned circuit to continue the actuation of the signal, substantially as set forth.

71. In a signaling system, in combination, 60 a signal and means for actuating the same, a commutator moving with the signal, a contact device with two separated contact-points and a contact part capable of contacting with only one of said points at a time, an electromagnet with coils of high resistance and the armature thereof controlling said contact device, a relay having pairs of opposed coils

and an armature between said coils, the cores of each pair of opposed coils being magnetically connected, a movable commutator-brush actuated by the armature of said relay, said commutator being provided with means for forcing said movable brush away from the commutator and forcing said relay-armature away from its forward position, means for 70 closing a circuit through such contact part and one of the contact-points of said contact device and through the front coil of one of said pairs of coils to cause a forward movement of the armature of said relay and for 80 holding said armature forward with the movable brush against the commutator by a circuit through the front and back coils of such pair of coils subject to the control of a train in advance of the signal, signal-operating 85 means of low resistance, and means for closing a circuit by the movable commutator-brush through the commutator and in series through front and back coils of a second pair of opposed coils in said relay and the coils of 90 said electromagnet and thereby causing the movement of said contact device so as to bring the other point in contact with such contact part and thereby closing a branch of said last-mentioned circuit through such sig- 95 nal-operating means of low resistance in multiple with the coils of said electromagnet and opening said circuit at the commutator at intervals in the movements of the signal subject to the closing of the first-mentioned circuit to continue the actuation of the signal, 100 substantially as set forth.

72. The combination, with a signal and controlling mechanism thereof, including a relay, of a movable contact-surface connected to and 105 moving with said signal constructed to force the armature-lever of the relay to rearward position, and two contact parts, comprising the armature-lever of the relay and a back contact, one of said parts being constructed 110 to spring over and engage the other when the armature is forced to rearward position, and one of said parts being provided with an insulated face constructed to contact with the other part and prevent electrical contact of 115 the parts when the armature moves rearwardly but is not forced to rearward position, substantially as set forth.

73. The combination with a signal located at the rear end of a block and constructed to 120 indicate the presence of a train in the block or the absence of a train from the block and automatic mechanism subject to the control of a train in the block for actuating said signal, of a dummy signal so located in rear of 125 said indicating-signal that under clear conditions of weather the indicating-signal will be visible from a train at the dummy signal, said dummy signal being located at a distance from the indicating-signal sufficient 130 and no greater than is necessary for bringing trains under such control that they can be stopped in rear of the indicating-signal, substantially as set forth.

74. The combination with a signal located at the rear end of a block and constructed to indicate the presence of a train in the block or the absence of a train from the block and 5 automatic mechanism subject to the control of a train in the block for causing said signal to continuously revolve to give the safety indication and to remain at rest to give the danger indication, of a dummy signal so 10 located in rear of said indicating-signal that under clear conditions of weather the indicating-signal will be visible from a train at the dummy signal, said dummy signal being located at a distance from the indicating-signal sufficient and no greater than is necessary for bringing trains under such control 15 that they can be stopped in rear of the indicating-signal, substantially as set forth.

75. In a signaling system, in combination, a 20 signal and means for actuating the same, a relay having opposed coils and an armature between said coils and means for closing a circuit differentially through the coils of such

relay to actuate the armature thereof in the direction required for the safety indication 25 and opening said circuit by such movement of the armature and supplying electric current to said relay to hold the armature in the position to which it has been moved, from a circuit subject to the control of a train in 30 advance of the signal, means for closing a circuit by the movement of the armature for causing the operation of the signal-actuating means, and means compelled to move with the signal in giving the safety indication and 35 by such movement forcing the armature in the direction required for the danger indication, substantially as set forth.

Signed at the borough of Manhattan and city of New York this 5th day of December, 40 1899.

HENRY BEZER.
